CLAIM

The ornamental design for a golf divot tool carousel, as shown and described.

DESCRIPTION

FIG. 1 is a perspective view of a golf divot tool carousel showing my new design, the tools and ball marks adapted to be displayed therein being shown in phantom and forming no part of this new design;

FIG. 2 is a front elevational view thereof;

FIG. 3 is a right-side elevational view thereof;

FIG. 4 is a left-side elevational view thereof;

FIG. 5 is a rear elevational view thereof;

FIG. 6 is a top plan view thereof; and,

FIG. 7 is a bottom plan view thereof.
